UNITED STATES PATENT OFFICE.

HERMANN FRIEDRICH STEINMEYER, OF PFORZHEIM, GERMANY.

WATCHCASE.

SPECIFICATION forming part of Letters Patent No. 634,919, dated October 17, 1899.

Application filed March 17, 1899. Serial No. 709,470. (No model.)

To all whom it may concern:

Be it known that I, HERMANN FRIEDRICH STEINMEYER, a subject of the Grand Duke of Baden, and a resident of Pforzheim, in the 5 Grand Duchy of Baden, German Empire, have invented certain new and useful Improvements in Watch-Casings, of which the following is an exact specification.

The present invention relates to improvements in watches in which the work is contained within a special casing, and has for its object to provide an opening-and-closing device which can be actuated without injuring the mechanism of the watch, which hitherto often has been the case.

In my construction I use a spring provided with a locking and lifting spring and opening the cover of the casing when pressing upon a button suitably attached to said spring. The chief feature of my invention is that the cover of the watch-casing can be opened and closed without the winding-stem suffering under the pressure necessary to effect the opening, thereby injuring the mechanism. The winding-stem of the watch is fixed in different positions by means of pawls engaging into notches provided at different places of the winding-stem. When this latter is fixed in its lowest position, the locking and lifting spring can effect the opening of the cover of the casing without the winding-stem being actuated in any way, and while in this position the watch may be wound up. When the winding-stem is drawn upward, the pawls engage into the lower notch and no connection will be between the winding-stem and the mechanism. Consequently the inner casing can be opened.

My invention will be more fully understood with reference to the accompanying drawings, in which similar letters denote similar parts throughout the different views, and in which—

Figure 1 shows a watch-casing on a large scale, the cover being opened in dotted lines and the inner casing containing the mechanism being partly opened in dotted lines. Fig. 2 shows a vertical section, on a large scale, through the pendant containing the opening mechanism. Fig. 3 illustrates a vertical section rectangular to Fig. 2 and made through line xx of Fig. 1. Fig. 4 illustrates the spring h when the cover of the casing is closed. Fig.

5 is a horizontal section through line yy of Fig. 2. Fig. 6 is the same through line zz of Fig. 3. Figs. 7 and 8 represent detail views 55 of the spring h and the guide i .

The watch-casing consists of a casing proper, a , having a pendant b rigidly connected to its top, and a cover c hinged to the lower extremity of the casing. Within this outer casing a an inner casing e , serving to take up the mechanism, is arranged, adapted to rotate by means of a joint d . The cover c and the inner casing e are kept in place by means of a spring g , having a locking and lifting spring 60 ff' . The spring g is connected to the cover c by means of a spring-arm g' and a connecting-rod g'' . The automatic opening of the cover will be effected as soon as the locking-spring f' , retaining the cover, is released. 7c The spring g is kept in position by means of a second spring h , being of circular form and having lateral projections $h' h'$ and noses $h^2 h^2$, Fig. 7. Around this spring h a guide i is provided, carrying elastic arms $i' i'$, Fig. 8. This 75 guide i , forming the bearing of the spring h , is rigidly connected to the pendant b by means of the screws i^3 , Figs. 2 and 3. The spring h is arranged in such a manner that its noses h^2 are located between the arms $i' i'$ of the 80 guide-spring i .

Between the springs h and i a rod k is located. The lower extremity of this rod is connected to a winding-stem l . The top of the rod k is formed into a knob m , serving to 85 lift and to turn the winding-stem l . The rod k is provided with two notches k' and k^2 . Between these two notches the rod k is enlarged somewhat and forms an oval piece k^3 . The knob m is brought in connection with the 90 pendant b by means of a tube m' , sliding within the pendant b . The rod k , and consequently the winding-stem l , can be retained in two different positions—first, in a low position, and, secondly, in a high position. This 95 retaining or fixing of the rod k is effected by the noses h^2 , engaging either into the notch k' or k^2 . When the rod k is raised, the oval part k^3 spreads somewhat the spring-arms i' of the guide-spring i . Both positions of the 100 winding-stem l and of the rod k —that is to say, the lowest position in which the mechanism can be wound up and the highest position in which the winding-stem l is out of

connection with the mechanism—are represented in Figs. 3 and 4.

Fig. 4 shows the lowest position of the spring, in which the lateral projections $h' h'$ of the spring h press against the heads $i^2 i^2$ of the spring-arms $i' i'$. In the lowest position of the rod k the spring h can be pushed downward by pressure exerted upon a button n , provided within the knob m for winding up the mechanism. This pressure can be effected without the winding-stem l for winding up the mechanism being actuated in any way. The independent motion in this case is attained by a disk q , located above the spring h and connected to the button n by tongues p . As soon as the locking-spring f' is released the cover c will open.

The mechanism is actuated in the following manner: When the casing a is closed and the button n is pressed down, the movement is transmitted by the tongues p to the disk q and from there to the spring h and to the spring g . The latter is pressed down, and the locking-spring f' liberates the casing-cover, which then will open automatically by action of the spring g' and the rod g^2 . When the button n is liberated and the knob m for winding up the mechanism is drawn upward, the spring-arms $i' i'$ are spread somewhat by the oval part k^3 of the rod k . At the same time the spring h is pushed upward by the spring g , so that the projections $h' h'$ of the spring h keep spread the heads $i^2 i^2$ of the spring-arms $i' i'$ —that is to say, the spring h , with its lateral projections $h' h'$, is fixed. (See Fig. 3.) When the rod k is drawn farther upward, the noses $h^2 h^2$ engage into the lower notch k^2 , and the rod k is fixed in this lower position. Now the inner casing containing the work is released from the locking-spring f and can be removed. In again pushing downward the knob m the projections $h' h'$ of the spring h are drawn out of the heads $i^2 i^2$ of the spring-arms $i' i'$, when the oval part k^3 of the rod k passes through these heads and spreads them.

The spring h then takes the position shown in Figs. 2 and 3. The spring h is now again in its original position and submitted to the movements of the button n , thus merely effecting the opening of the cover c .

Having thus fully described the nature of this invention, what I desire to secure by Letters Patent of the United States is—

1. In watch-casings, the combination with a main casing a , an inner casing containing the mechanism e , and a cover c , both movably connected to the main casing a , a pendant b located at the top of the casing a , a rod k carrying a knob m , notches $k' k^2$ provided in said rod, a winding-stem l attached to the lower extremity of the rod k , a spring g , a button n , means to connect said button to the locking-springs $f f'$ arresting and liberating the cover c , a spring-arm g' connected to the spring g and means to transmit the pressure effected upon the button n , a circular spring h having lateral projections $h' h'$ and noses $h^2 h^2$, subsequently engaging with the notches $k' k^2$, a guide i with spring-arms $i' i'$ having heads $i^2 i^2$, the whole substantially as described.

2. In watch-casings, the combination of a circular spring h having lateral projections $h' h'$ and noses $h^2 h^2$, with a guide i surrounding said spring h and having spring-arms $i' i'$, with heads $i^2 i^2$, a plate q located above the spring h , tongues p connecting said disk to a button n , a spring g having a locking and lifting spring $f f'$ retaining and liberating the cover of the watch-casing, a rod k provided with notches $k' k^2$, a winding-stem l attached to said rod, a knob m forming the top of the rod k , substantially and for the purpose as set forth.

In witness whereof I have hereunto set my hand in presence of two witnesses.

HERMANN FRIEDRICH STEINMEYER.
